FORREST J. COUCH, OF CINCINNATI, OHIO, ASSIGNOR TO THE AMERICAN LAUNDRY MACHINERY COMPANY, OF CINCINNATI, OHIO, A CORPORATION OF OHIO

STRIPPING MEANS FOR FLAT WORK IRONERS

Application filed October 21, 1929, Serial No. 401,143. Renewed December 24, 1930.

This invention relates to improvements in stripping means for flatwork ironers, to prevent the work being ironed from adhering to and becoming wrapped around the ironing rolls.

Heretofore, it has been customary to encircle the set of ironing rolls with a transversely spaced series of longitudinally extending endless strings, ribbons or tapes, which have stripped the work from the rolls in a satisfactory manner but have marred the finished appearance of the work by leaving therein conspicuous impressions, particularly the impressions left by the strings and the selvaged or otherwise finished edges of the tapes and ribbons.

It is therefore the general object of the present invention to provide improved stripping means for flatwork ironers, which means effectively strips the work being ironed from the ironing rolls but does not leave therein any impressions whatsoever. The stripping means here provided comprises a series of endless tapes having longitudinal edge portions of gradually decreasing thickness. Specifically, the present tapes are made of the same fabric material as the ironing roll covers and have frayed longitudinal edge portions. As the result of the particular material of which they are made and of their frayed portions, these tapes leave no impressions whatsoever in the work, so that the finished appearance thereof is in no way marred by the use of these tapes.

Further objects of the invention are in part obvious and in part will appear more in detail hereinafter.

The invention will be readily understood from the following description taken in connection with the accompanying drawings, in which Fig. 1 is a side elevation of a flatwork ironer with the present stripping tapes applied thereto, said ironer being shown in dash-dot lines; Fig. 2 is a plan view of the ironer and the present stripping tapes, the ironer being shown in dash-dot lines; Fig. 3 is a plan view of one of the spring take-up devices used with the present stripping tapes; Fig. 4 is a vertical sectional view of said take-up device, the view being on the line 4-4,

Fig. 3; Fig. 5 is a detail sectional view of one of the present stripping tapes and the spring take-up device therefor the view being on the line 5-5, Fig. 3; and Figs. 6 and 7 are respectively a plan view and a cross sectional view of one of the present stripping tapes.

The ironing machine illustrated in the drawings is of the conventional type and therefore includes a frame 1 having mounted thereon a set of heated ironing chests 2. Operating with said chests and mounted in suitable bearings in said frame are a set of ironing rolls 3, a six-roll ironer being here shown. These rolls are provided with suitable padding (not shown) comprising inner padding material of cork, springs or the like and an outer cover cloth of canvas, muslin, or the like, as is usual. For applying pressure between the ironing rolls and the ironing chests for the ironing operation, two pressure bars 4 are provided, one at each side of the machine for cooperation with the roll ends.

The work to be ironed is fed through the machine by the rotation of the ironing rolls and it has been found necessary, or at least desirable, to provide means for preventing the work from adhering to and becoming wrapped around said rolls. Heretofore, strings, ribbons and tapes have been used for this purpose, and while they have stripped the work from the rolls in a satisfactory manner, they have marred the finished appearance of the work by leaving therein objectionable impressions, the impressions formed by the strings and the selvaged or otherwise finished edges of the ribbons and tapes being particularly conspicuous.

The present improved stripping means comprises a series of endless tapes 6 which encircle the ironing rolls, being suitably spaced along their length, as clearly indicated in Fig. 2. Said tapes have middle body portions 7 of substantially uniform thickness and longitudinal edge portions 8 of gradually decreasing thickness toward their edges. The material of which the tapes are made is preferably of the same fabric character as the ironing roll cover cloths and the work being ironed. The particular tapes here illustrated are made of the same fabric material as the cover cloths

of the ironing rolls, that is, of canvas, muslin or the like, and have their longitudinal edge portions frayed, as best shown in Figs. 6 and 7. As the result of the material of which they are made, and of their frayed edges, the present tapes leave no impressions whatsoever in the work, so that the finished appearance of the work is in no way marred by the use thereof.

10 The tapes, which in practice are one inch wide with one fourth inch frayed portions, lie, of course, between the work passing through the machine and the ironing rolls and effectively prevent the work from wrapping around said rolls, as will be readily understood.

In order to hold the upper stretches 11 of the tapes out of contact with the ironing rolls, as indicated in Fig. 1, suitable take-up devices are provided therefor, as is usual. In the present embodiment of the invention, a spring take-up device is provided for each tape and as the several take-up devices are of identical construction, a description of one 25 will suffice for all.

Mounted on the forward end of each of the two pressure bars 4 is a bracket 12 and in these two brackets are rigidly mounted the ends of a shaft 13. Mounted on this shaft, in proper spaced relation, are the several take-up devices, one for each tape.

Each take-up device is made of a one piece heavy wire bent to provide an anchoring end portion, a tape-supporting end portion and an intermediate portion 18 connecting said end portions. The anchoring end portion is formed into two eyes 19 and 20 loosely encircling shaft 13 and joined by a bridge 21. Suitably secured to said bridge is one end 22 of a spring 23 coiled around shaft 13 and having its other end 24 suitably secured thereto, such as by being anchored in the aperture 25 thereof (Fig. 5). The securement of the spring end 24 to shaft 13 prevents movement 45 in one direction of the take-up device along said shaft, and to prevent movement of the take-up device along the shaft in the other direction, a cotter or other pin 27 extends through said shaft and engages the spring 50 end 22, as best shown in Fig. 3.

The intermediate connecting portion 18 of the wire extends directly forwardly from the top of eye 19 of the anchoring end portion and is, therefore, substantially normal thereto. The tape-supporting wire end portion 30 extends perpendicularly from the forward end of connecting wire portion 18 and therefore is substantially parallel with the anchoring wire end portion. Rotatably mounted on the tape-supporting wire end portion is a roller 32 having an annular tape-receiving groove 33 of concave shape in cross section, said shape preventing folding of the frayed tape edge portions 8. This roller is prevented 65 from escaping at one side by the connecting

wire portion 18 and at the other side by a cotter pin 34 extending through the wire end.

The stripping tapes 6 pass, therefore, at the forward end of the machine around the end ironing roll 3a and the rollers 32 of the take-up devices. At the rear end of the machine, the tapes pass around the end ironing roll 3b and the stationary bar 35 carried by brackets 36 mounted by means of pins 37 on the rear ends of the pressure bars 4.

What I claim is:

1. In an ironing machine of the type having an ironing chest and a padded ironing roll cooperating therewith and between which chest and roll the work is passed for the ironing operation, and means for stripping the work being ironed from said roll and comprising a tape adapted to be passed through the machine with the work, being interposed between the work and the ironing roll, said tape having a middle body portion of substantially uniform thickness and longitudinal edge portions of a thickness gradually decreasing toward the outer edges thereof.

2. In an ironing machine of the type having an ironing chest and a padded ironing roll cooperating therewith and between which chest and roll the work is passed for the ironing operation, and means for stripping the work being ironed from said roll and comprising a fabric tape adapted to be passed through the machine with the work, being interposed between the work and the ironing roll, said tape having a middle body portion of substantially uniform thickness and frayed longitudinal edge portions of appreciable width.

3. In an ironing machine of the type having an ironing chest and an ironing roll cooperating therewith and between which chest and roll the work is passed for the ironing operation, said roll being padded and covered with a fabric cover cloth, and means for stripping the work being ironed from said roll and comprising a tape adapted to be passed through the machine with the work, being interposed between the work and the ironing roll, said tape being made of the same fabric material as said ironing roll cover cloth and having frayed longitudinal edge portions of appreciable width.

4. In an ironing machine of the type an ironing chest and a padded ironing roll cooperating therewith and between which chest and roll the work is passed for the ironing operation, means for stripping the work being ironed from said roll and comprising an endless fabric tape encircling said ironing roll and having frayed edge portions of appreciable width, said tape lying between the work and the ironing roll and thus serving to prevent the work from wrapping around said roll, and a take-up device for said tape having a roller over which said tape passes,

said roller having an annular tape-receiving groove of concave shape in cross section, said shape preventing folding of the frayed tape edge portions.

5 5. In an ironing machine of the type having an ironing chest and an ironing roll cooperating therewith and between which chest and roll the work is passed for the ironing operation, said roll being padded and covered with a fabric cover cloth, and means for stripping the work being ironed from said roll and comprising a tape adapted to be passed through the machine with the work, being interposed between the work and the 10 ironing roll, said tape being made of a fabric material corresponding to the fabric material of the cover cloth of said ironing roll and having frayed longitudinal edge portions of appreciable width.

15 20 In testimony whereof I hereby affix my signature.
